UNITED STATES PATENT OFFICE.

JOHN R. WELLBORN, OF ATLANTA, GEORGIA.

SODA-FOUNTAIN ATTACHMENT.

1,286,460.

Specification of Letters Patent.

Patented Dec. 3, 1918.

Application filed May 18, 1918. Serial No. 235,271.

To all whom it may concern:

Be it known that I, JOHN R. WELLBORN, a citizen of the United States, residing at Atlanta, in the county of Fulton and State 5 of Georgia, have invented certain new and useful Improvements in Soda-Fountain Attachments, of which the following is a specification.

This invention is a soda fountain attachment and has for its principal object the production of a device which is attached to the carbonated water faucet for efficiently projecting the carbonated water into a glass for thoroughly mixing the water with the 15 syrup.

Another object of this invention is the production of a soda fountain attachment which eliminates the necessity for mixing the syrup and carbonated water by the usual 20 method of stirring with a spoon, since the device is constructed so as to inject carbonated water into the glass at the inner bottom portion thereof, thus thoroughly mixing the water with the syrup and having 25 the soda in condition for serving by the time the glass is filled.

Another object of this invention is the production of a soda fountain attachment which consists of a tube which is to be connected 30 to the carbonated water faucet, this tube having apertures adjacent its lower end by which the water may escape into the glass at the lower portion thereof to mix with the syrup at the bottom of the glass, while 35 a yieldable cap is carried at the lower portion of the tube for closing the lower end and also constituting a bumper for preventing the lower end of the tube from striking and breaking or injuring the bottom of the 40 glass.

Broadly stated, this invention consists of a hollow elongated tube having a flange at its upper end thus permitting a securing or locking nut to be connected thereto and also 45 connected to the carbonated water faucet, for holding the tube in a set position, said tube having apertures formed therethrough adjacent its lower end, thus permitting water to pass downwardly through the tube 50 and be dispensed through the apertures, and a yieldable plug carried by the lower end of the tube projecting beyond the side surface of the tube, thus preventing the glass from striking the lower end of the tube and 55 consequently preventing injury to the glass.

One practical form of construction and

assembly of the present invention will be hereinafter described and is illustrated in the accompanying drawing, in which—

Figure 1 is a side elevation of the soda fountain attachment, illustrating the manner in which the same is inserted into a glass, and

Fig. 2 is a central longitudinal section through the device.

In the preferred embodiment of the present invention, about to be described, 5 indicates the tube, which as illustrated herein, is elongated and is preferably cylindrical. Of course, it may be of any other desired 70 shape without departing from the spirit of the invention as long as the tube is long enough to permit of its passing into the lower portion of a glass. This tube 5 is provided with an annular flange 6 upon its 75 upper end, this flange extending outwardly and provided with a gasket 7. It is obvious the flange may be secured to the carbonated water faucet in any suitable manner, although the securing does not enter into 80 the present invention and for this reason is not being deemed necessary to be herein illustrated.

The lower end of the tube 5 is closed by a plug 8. This plug 8 is formed of yieldable 85 material, such for instance, as soft rubber. The plug comprises a body which is substantially the same diameter as the tube 5, thus being insertible in the lower end of the tube, as shown in Fig. 2. The body of 90 this plug is provided with an annular flange 9 extending outwardly therebeyond and this flange extends beyond the side surfaces of the tube 5, thus causing the flange 9 to prevent a glass from accidentally striking the 95 lower end portion of the tube 5. This plug 8 is also provided with a substantially conical lower surface 10, thus facilitating the passing of the plug through the contents of the glass.

An annular row of apertures 11 are formed in the tube 5 at a point adjacent the lower end thereof and these apertures 11 may slant slightly downwardly toward their outer ends, as illustrated in Fig. 2. It will 105 be noted that the apertures are formed at a point above the inner end of the plug 8, thus preventing the plug from obstructing free passage through the apertures.

For the purpose of illustrating the operation of the invention a glass is indicated in general at 12. As above stated, the attach-

ment is secured to the carbonated water faucet. In the usual practice, it is necessary to place the syrup within the glass and then after the glass has been filled with carbonated water, it is customary to stir the water and the syrup to mix the same by the use of a spoon. With the present invention however, the syrup is placed within the glass and any other cooling substance such as ice or ice cream is placed therein. The glass is then placed around or inserted over the lower end of the tube 5, as illustrated in Fig. 1. The carbonated faucet water may then pass through the tube and will of course be discharged through the apertures 11. As these apertures are adjacent the lower end of the tube, it is obvious the force of the carbonated water will cause the water to be thoroughly mixed with the syrup at the bottom of the glass and will continue to thoroughly mix with the syrup until the glass is filled. As above stated, if so desired, the apertures may slant downwardly toward their outer ends and thus cause the carbonated water to be directed downwardly to thoroughly mix with the syrup. The provision of the plug at the lower end of the tube will prevent the bottom of the glass or the side portions of the glass from being injured since the flange 9 of the plug will hold the glass from engagement with the lower portions of the tube, while the conical portion 10 of the plug will allow the plug to pass through the contents of the glass although when striking the bottom of the glass will limit further movement of the glass without injury to the glass.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

50 1. A device of the class described, comprising an elongated hollow tube, said tube having securing means upon one end thereof, a yieldable plug carried within the re-

maining end of said tube, said plug comprising a body having an annular flange formed thereon, said last mentioned flange extending beyond the side surface of said tube, thus preventing a glass positioned over the end of said tube from being injured, the lower end of said plug being substantially conical and extending to the periphery of said flange for facilitating the passing of the plug through the glass, and said tube having an annular row of apertures formed therethrough adjacent said plug, said apertures slanting downwardly toward their outer end, thus permitting water to be passed through the tube and to be dispensed downwardly therefrom through said apertures.

2. A device of the class described comprising an elongated hollow tube, said tube having securing means upon one end thereof, a yieldable plug carried within the remaining end of said tube, said plug comprising a cylindrical body having an annular flange formed thereon, said last mentioned flange extending beyond the side surface of said tube, thus constituting a shield for preventing a glass positioned over the tube from striking the tube, the lower end of the plug being substantially conical and extending to the periphery of the flange for forming a slanting lower surface which will deflect material engaging the same to permit the plug to pass through said material, and said tube having apertures formed therethrough adjacent said plug.

3. A device of the class described comprising an elongated hollow tube, said tube having securing means at one end thereof, a closure at the opposite end of said tube, said tube having an annular row of apertures drilled therethrough adjacent said plug, said apertures slanting downwardly toward their outer ends, thus causing water to pass from the tube through said apertures to be dispensed downwardly in a conical formation.

In testimony whereof I affix my signature in presence of two witnesses.

JOHN R. WELLBORN.
